UNITED STATES PATENT OFFICE

ALBERT B. CLEVELAND AND SAMUEL W. BAILEY, OF HACKLEBURG, ALABAMA

HARROW

Application filed May 19, 1931. Serial No. 538,521.

This invention relates generally to harrows employed in agricultural operations and particularly to a new and novel harrow, embodying a new arrangement of cutting elements and a novel type of ground severing blades.

It is an object of this invention to provide a new and novel harrow of the type described which employs in a new association a plurality of non-rotatable ground engaging blades.

It is also an object of this invention to provide a simple, inexpensive and very durable and satisfactory riding harrow of the type described, which may be constructed considerably cheaper than the disk and certain other types of riding harrows.

It is also an object of this invention to provide a riding harrow of the type described wherein means is provided to attach and combine therewith drag means whereby to condition the ground after the passage of the harrow blades.

These and other objects of the invention, its nature, and its composition and arrangement and combination of parts will be readily understood by anyone acquainted with the art to which this invention relates upon consulting the following descriptions of the drawings, in which:—

Figure 1 is a general top plan view of the device of my invention showing the arrangement of parts thereof.

Figure 2 is a side elevational view of Figure 1.

Figure 3 is an enlarged perspective view of one of the harrow blades.

Referring in detail to the drawings it will be seen that the frame 5 of the riding harrow is composed of a forward harrow blade carrying angle iron 6 connected to a similar rearward angle iron 7 by means of flat bars 8 and 8a downturned at their ends 9, the downturned end portions 9 being disposed to abut the vertical flange of the angle bars 6 and 7 and to be bolted thereto by means of bolts

10. The rearward downwardly bent portions 9 of the flat bars 8 and 8a are likewise attached to the vertical flange of the rear angle beam 7, but by means of an eye bolt 11 providing means whereby a connecting link 50 12 secured to either end of a drag generally designated 13 is flexibly connected to the frame and to the drag, the end connecting the drag being placed through an eye 14 on a bolt 15 placed through the drag. 55

The angle iron beams 6 and 7 of the frame 5 are not of the same length, the beam 7 being longer than the beam 6. The beams are centrally connected by another flat bar 16 having downturned ends similar to the downturned ends on the flat horizontal bars 8 and 8a, and bolts 17 connect the bar 16 to the beams 6 and 7 in the same manner as obtains in the case of the bars 8 and 8a. Projecting forwardly from the vertical flange of the beam 6 is a pair of eyes 18, 18, to each of which is connected one leg 19 of a draft means generally designated 20. The legs 19 meet in an eye 21 held positioned by a suitable locking ring 70 22. A suitable seat 23 is supported on an angularly disposed bar 24 secured intermediate the ends, and upon the upper surface of the bar 16, and a foot rest or cross piece 25 is secured to the upper surface of the bar 16 75 forwardly of the angular piece 24.

Secured by means of bolts 26 to the forward side of both the front and rear angle iron beams 6 and 7 are peculiarly shaped ground engaging blades generally designated 27. 80

Each of these blades consists of an L-shaped portion 28 adapted to be disposed in generally horizontal position with the upright portion 29 apertured to receive at 30 one of the bolts 26, so as to abut the upright portion 29 to the forward face of the flange of either the beam 6 or the beam 7 in the positions shown in the drawings. From the free end of the horizontal portion 31 of the L-shaped section depends in rearward downward angular re- 85 90

lationship the blade portion indicated at 32. The blade is formed preferably by twisting an extension of the horizontal portion 31 at right angles thereto and depressing the same 5 so as to form a curved blade having the relationship with the harrow frame and the ground clearly seen in Figure 2. The blades are adapted to extend rearwardly as shown in Figure 1 at approximately right angles to 10 the beams 6 and 7. The blade portion 32 has the general form seen in the drawings, being elongated and having a curved upper edge and a curved lower edge and a rear lower portion 33 sharply curved upwardly. The lower 15 edge of the portion 33 is beveled to provide a sharp edge as indicated at 34. The angularity and sharpness of the blades is adjusted to conditions to be contended with and according to the depth of cut desired. The drag 13 20 may be of any suitable kind and may be detached if desired, but the idea of the invention is to harrow and condition the ground in a single operation which ordinarily would require the services of several additional persons and at least two machines, thereby saving 25 time, labor and effort in properly conditioning the ground for agricultural purposes.

It is to be noted particularly, that the blades 30 on the front beam 6 are so disposed that they come between blades on the rear beam 7 and that the end blades of the beam 7 are positioned outside of the end blades of the beam 6.

It is to be definitely understood that I do 35 not desire to limit the application of this invention to the particular modification set out herein to illustrate the principles thereof, and any change or changes may be made consistent with the spirit and scope of the invention.

What is claimed is:—

1. A harrow of the type described, comprising, a frame consisting of a pair of transverse parallelly spaced beams, a plurality of 45 longitudinally disposed flat bars connecting said beams, a seat on one of said bars, draft means on the forward of said beams, and downwardly and rearwardly directed elongated arcuate harrow blades extending from 50 each of said beams, the blades of the forward beam being disposed to come between the harrow blades of the rearward beam.

2. A harrow of the type described, comprising, a frame consisting of a pair of transverse parallelly spaced beams, a plurality of 55 longitudinally disposed flat bars connecting said beams, a seat on one of said bars, draft means on the forward of said beams, and downwardly and rearwardly directed elongated arcuate harrow blades extending from 60 each of said beams, the blades of the forward beam being disposed to come between the harrow blades of the rearward beam, each of 65 said blades comprising, a flat, elongated bar having a curved sharpened edge presented to-

ward the ground in a vertical plane, a twisted portion at one end of the bar resulting in a plane portion substantially at right angles to the remainder of the blade, and an upright portion on the plane portion, the plane portion being adapted to engage the underpart 70 of one of said beams, and the upright portion being adapted to engage and be secured to the forward part of one of said beams.

In testimony whereof we affix our signatures.

ALBERT B. CLEVELAND.
SAMUEL W. BAILEY.
